CLAIM

The ornamental design for a lock with digital control, as shown and described.

DESCRIPTION

FIG. 1 is a perspective view of a lock with digital control showing my new design;

FIG. 2 is a front elevational view thereof;

FIG. 3 is a rear elevational view thereof;

FIG. 4 is a left side elevational view thereof, the right side being a mirror image of that shown;

FIG. 5 is a top plan view thereof; and

FIG. 6 is a bottom plan view thereof.

The right and left-hand sides are identical.
